(57) **CLAIM**

The ornamental design for a handle assembly for a cleaning tool, as shown and described.

DESCRIPTION

FIG. 1 is a perspective view of one embodiment of the new design for a handle assembly for a cleaning tool;

FIG. 2 is a right side view thereof, the left side view being a mirror image of the right side view;

FIG. 3 is a top view thereof;

FIG. 4 is a bottom view thereof;

FIG. 5 is a front view thereof; and,

FIG. 6 is a rear view thereof.

The long-short-long broken lines immediately adjacent the shaded areas represent the bounds of the claim and all other broken lines are for illustrative purposes only. None of the broken lines form a part of the claimed design.
